UNITED STATES PATENT OFFICE

2,474,417

HEATING APPARATUS FOR BURNING A
LIQUID FUEL SPRAY

George A. Gillen, Bronx, N. Y.

Application December 12, 1944, Serial No. 567,888

1-Claim. (Cl. 158-4)

1

The invention herein disclosed relates to heating apparatus generally.

Objects of the invention are to accomplish both more efficient combustion and more effective transfer of heat from the combustion products to a surrounding media, such as water in a boiler or the like.

Particularly it is an object of the invention to accomplish a better, more thorough and more uniform admixture of air and oil fuel and to maintain that mixture during flame propagation in a continuing state and so controlled and confined as to best effect the desired heat exchange.

Other and more specific objects, as well as the novel features by which the purposes of the invention are attained, will appear or are definitely set forth in the course of the following specification.

The drawing accompanying and forming part of the specification illustrates present practical embodiments of the invention but as such illustration is primarily for purposes of disclosure it will be recognized that structure may be modified and changed as regards the illustration, all within the true intent and broad scope of the invention as hereinafter defined and claimed.

Fig. 1 in the drawing is a broken vertical sectional view of a heating unit embodying features of the invention;

Figs. 2 and 3 are broken transverse sectional views of the same as on substantially the plane of lines 2-2 and 3-3 of Fig. 1;

Fig. 4 is a broken longitudinal sectional view of a modified form of the invention;

Fig. 5 is a transverse sectional view as on substantially the plane of line 5-5 of Fig. 4.

Fig. 1 illustrates a heating unit of the hot water or steam boiler type having a water space 7 through which extends a submerged horizontal cylindrical chamber 8.

This chamber may have a lining of stainless steel, porcelain, fire clay, tile, brick or other suitable heat transfer medium 9.

Projecting into one end of the cylindrical combustion chamber described, and extending to near the opposite end of the same is an air supply tube or conduit 10. A suitable source of air supply such as a blower 11, is connected with the outer end of tube 10.

In the opposite end portion of the chamber, spaced from and opposite the open end of the air tube, is a fuel injector shown as of the type disclosed in the George A. Gillen Patent No. 2,107,891 of February 8, 1938, and comprising a piston sleeve 12 operating in a casing 13, said sleeve having

2

atomizing ports 14 which will be opened to discharge fuel between the end of the casing and the head 15 of the sleeve when the sleeve is projected against the tension of the retracting spring 5 by pressure of the oil in the central nozzle tube 16. In the illustration oil is supplied through pipe 17 into the central nozzle portion of the injector from a suitable pump indicated at 18.

The end wall of the chamber is shown as annularly concave at 19 about the injector, with the head of the injector centrally disposed at the crest of the inner rim of the annulus, to form a flow reversing baffle and deflector, and a control for streaming the atomized fuel off into the vortex of the reversed air flow.

Proper admixture of air and fuel also is aided by provision of an expanded or flaring rim 20 on the end of the air tube, which may be angled or curved more or less complementary to the curvature at 19, to confine, guide and more or less restrict the reversed flow and to sheet it into an annular stream against the cylindrical wall of the chamber.

The air tube, spaced as it is within the cylindrical chamber, forms an elongated annular combustion space 21 about the same, confining the products of combustion for their full length of travel in the combustion chamber against the cylindrical wall of that chamber and, at the

30 inside, against the wall of the air tube. In this manner an effective double heat exchange is accomplished, from the burning products of combustion outwardly to and through the surrounding wall of the chamber to heat the water or other medium about that chamber, and inwardly to and through the wall of the tube to thoroughly and continuously heat the entering air being supplied to the injector.

In this manner controlled combustion and continuing substantially uniform flame propagation can be regulated and maintained.

With combustion completed the products are permitted to escape from the elongated annular combustion space, at the end opposite the injector, through the exhaust pass 22, opening into a horizontal flue 23 leading to a stack or other outlet 24.

Heat extraction means may be disposed in any 50 or all of the passages last described, for example as transverse passages 25, extending across the horizontal flue 23 and open at opposite ends to the water or other medium within the boiler or encasing structure 26. These transverse passages 55 may be disposed in offset relation, as indicated in

Fig. 1, so as to serve as baffles and control deflectors for the escaping flue gases.

To prevent any dead pockets at the exhaust end of the combustion chamber, the wall at that end may be annularly concaved as indicated at 27, to reverse and direct the flow to the discharge outlet.

For additional control purposes the air tube, instead of being horizontal and coaxial with the combustion chamber, may be inclined as indicated in Figs. 4 and 5, extending on an upward incline from the entrance end so as to direct the products of combustion largely downward at the mixture forming and ignition end so as to fully reach and traverse all portions of the bottom of the combustion chamber and to be forced laterally over such bottom wall by the gradually reduced cross sectional area below the air tube in the direction of flow toward the outlet end of the chamber. This eccentricity also provides increase in space above the tube in the direction of flow toward the outlet.

The invention provides both an ample supply of air and the complete preheating of that full volume of air before admixture with the fuel. The flow of incoming air practically the full length of the combustion chamber enables preheating or superheating sufficient to effect proper combination with any of the low grade, as well as medium or better grade fuels. The contra flow of air and fuel and the reversal of flow of the injected air at and about the atomized fuel admitted into the bowl formation 19, Fig. 1, and 19a, Fig. 4, at the end of the chamber assures thorough and substantially uniform and complete mixture and flame propagation.

Suitable means such as a spark plug indicated at 28 may be provided for ignition, this being usually located in the circular cavity surrounding the injector and atomizer.

What is claimed is:

Heating apparatus comprising an elongated, substantially horizontally extending, substantially cylindrical combustion chamber having an outlet at one end, an air supply tube entered through said outlet end of said combustion chamber and extending to near the opposite end of the combustion chamber, said air supply tube spaced from the surrounding walls of the combustion chamber and providing therewith an annular

combustion space substantially the full length of the combustion chamber, a flow reversing baffle at the last mentioned end of the combustion chamber opposite the discharge end of the air tube and arranged to reverse flow from said air tube and direct the same back into the annular combustion space surrounding said tube, a fuel injector at the center of said baffle and directed toward the discharge end of said air supply tube and means connected with the outer end of said tube for forcing a supply of air through said tube to said flow reversing baffle and fuel injector at the far end of the same and whereby injected fuel will be combined with preheated air issuing from the air supply tube and the combination be caused to burn as a combustible mixture in the annular combustion space about the air tube, imparting heat interiorly to the air supplied through the air tube.
